FREDERICK W. ANDREW
BY
A. Alexander Thomas
ATTORNEY

UNITED STATES PATENT OFFICE.

FREDERICK W. ANDREW, OF BROOKLYN, NEW YORK, ASSIGNOR TO EISEMANN MAGNETO CORPORATION, OF BROOKLYN, NEW YORK, A CORPORATION OF NEW YORK.

TELEPHONE RECEIVER OF THE WATCHCASE TYPE.

Application filed April 20, 1922. Serial No. 555,782.

To all whom it may concern:

Be it known that I, FREDERICK W. ANDREW, a citizen of the United States, and a resident of the city of New York, borough 5 of Brooklyn, county of Kings, and State of New York, have invented certain new and useful Improvements in Telephone Receivers of the Watchcase Type, of which the following is a specification.

10 My invention relates to telephone receivers of the so-called watch-case type and its object is to provide an improved device of that kind in which efficiency of operation is combined with extreme simplicity of construction. My new telephone receiver is 15 particularly adapted for radio work, although not limited to that field.

The advantages of my invention will become clear from a detailed description of the 20 accompanying drawings, in which—

Figure 1 shows an interior view of the shell or casing containing the magnet and coils;

Fig. 2 is a transverse cross-section of the 25 receiver shown in Fig. 1, with the cap and diaphragm in position on the casing;

Fig. 3 is a detached rear view of the magnet and its coil-carrying pole pieces; and

Fig. 4 is a detached perspective view of 30 one of the pole pieces.

The shell or casing 1 is of shallow cylindrical form and is made of a suitable non-magnetic material, such as aluminum or the like. The back end of the casing is closed 35 by a wall 2 and the other or front end is open, so as to receive the usual vibratory diaphragm 3 which is held in place by a cap 4 of insulating material. The cap 4 is screwed on to the casing 1 by means of co-operating screw threads 5. The cap 4 is at 40 the center provided with the usual sound opening 6.

Within the shell or casing 1 is a permanent magnet M in the form of a complete 45 ring and shaped to fit snugly in the casing. The magnet M is usually made of hard magnet steel, so as to retain its magnetism for a considerable period of time. The magnet has a pair of soft iron pole pieces indicated 50 as a whole by P and P¹. These pole pieces are substantially L-shaped and each consists of a base portion 7 and a polar extension 8. The polar extensions 8 are adapted to re-

ceive coils C and C¹. These coils are connected in series, as indicated at 9.

As illustrated in Fig. 2, the back wall 2 of the casing has a pair of holes 10, the magnet M has a pair of holes 11, and the pole pieces P and P¹ are provided with holes 12 in the base portion 7. Through the aligned holes 10, 11 and 12 pass metallic fastening members, such as screws or bolts 13, which are insulated by insulating washers 14 and 15 and by insulating sleeves 16, or in any other suitable way. The screws or bolts 13 have each a pair of nuts 17 and 18, which bear against the washers 14 and 15, respectively, and by means of which the magnet M and pole pieces P and P¹ are rigidly clamped to the back wall of the casing. The coils C and C¹ are connected to the inner ends of the fastening members 13 by wires 19 and 20 respectively. This connection is preferably permanent and may be secured by soldering or in any other convenient manner. The outer ends of the fastening members 13 are provided with readily adjustable nuts 21 to permit clamping of electrical conductors between the nuts 17 and 21. In other words, the fastening members 13 also act as binding posts for the coils C and C¹ to connect them in circuit. This double function of the members 13 considerably simplifies the construction and correspondingly reduces the cost of manufacture.

It will be seen from the foregoing that I have provided a telephone receiver possessing the combined advantages of simplicity of construction and efficiency of operation. The ring magnet M provides a divided magnetic circuit and has a greater magnetic length than a same-size magnet of the opening structure. The construction is so simple that there is very little mechanism in the shell or casing, and it is well known that an empty sound box gives a better effect than one cluttered with structural parts. As the parts of my new telephone receiver are very few and easily made and assembled, the cost of manufacture is reduced to a minimum.

What I claim is:

1. A telephone receiver of the watch-case type, comprising a non-magnetic circular shell or casing provided with a cap and diaphragm, a permanent ring magnet mounted in said casing and provided with

a pair of substantially L-shaped pole pieces, each pole piece having a base portion arranged between the magnet and back wall of the casing and a coil-carrying extension 5 projecting substantially at right angles to the plane of the magnet, and insulated metallic fastening devices passing through said magnet and the base portions of said pole pieces for securing these parts to the back 10 wall of the casing, said devices being constructed to serve as binding posts for the magnet coils.

2. A telephone receiver of the watch-case type, comprising a non-magnetic shell or 15 casing provided with a cap and diaphragm, a permanent magnet within said casing and having pole pieces provided with coils, said pole pieces having base portions arranged between the magnet and back wall of the 20 casing, and a pair of insulated screws or bolts passing through said magnet and the base portions of said pole pieces for securing these parts to the back wall of the casing, said screws or bolts being constructed 25 to serve as binding posts for said coils.

3. A telephone receiver of the watch-case type, comprising a non-magnetic shell or casing provided with a cap and diaphragm, a permanent magnet within said casing and

having pole pieces provided with coils, said 30 pole pieces being separate from the magnet and having each a portion in contact with the magnet, and a pair of insulated screws or bolts passing through said magnet and the contact portions of said pole pieces for 35 securing these parts to said casing, said screws or bolts being constructed to serve as binding posts for said coils.

4. A telephone receiver of the watch-case type, comprising a non-magnetic circular 40 shell or casing provided with a cap and diaphragm, the closed back wall of said casing having a pair of holes, a permanent ring magnet in said casing, a pair of pole-pieces 45 for said magnet, said pole-pieces consisting of polar extensions provided with coils and base portions extending between the magnet and back wall of the casing, said magnet and base portions having holes in alignment with said holes in the casing, and a pair of 50 insulated screws or bolts passing through said aligned holes for securing the magnet and pole-pieces to the back wall of the casing, said coils being connected to the inner 55 ends of said screws or bolts and the outer ends of said screws or bolts being adapted to act as binding posts.

FREDERICK W. ANDREW.
